UNITED STATES PATENT OFFICE.

EUGENE GRIESHABER, OF RIDGEWOOD, NEW YORK, ASSIGNOR OF ONE-HALF TO
MICHAEL SCHECKENBACH, OF RIDGEWOOD, NEW YORK.

SWING.

Application filed March 24, 1922. Serial No. 546,394.

To all whom it may concern:

Be it known that I, EUGENE GRIESHABER, a citizen of the United States, and a resident of the city of New York, Ridgewood, in the 5 borough of Queens, county of Queens, and State of New York, have invented a new and Improved Swing, of which the following is a full, clear, and exact description.

This invention relates to improvements 10 in lawn swings, an object of the invention being to provide a motor driven swing which will do away with the manual exertion ordinarily necessary to operate a lawn swing.

15 A further object is to provide a swing of this character, which may be manufactured either as a toy, or in full size for outdoor use, and a swing which will be simple and practical in construction, neat and attractive in appearance, strong and serviceable in use, unlikely to get out of order, and inexpensive to manufacture.

With these and other objects in view, the invention consists in certain novel features 25 of construction and combinations and arrangements of parts as will be more fully hereinafter described and pointed out in the claim.

In the accompanying drawings:—

30 Figure 1 is a view in longitudinal section through my improved swing on the line 1—1 of Figure 2;

Figure 2 is another view in longitudinal section taken at right angles to Figure 1 35 and on the line 2—2 thereof; and

Figure 3 is an enlarged fragmentary detail sectional view on the line 3—3 of Figure 2.

Referring in detail to the drawings, I 40 have used the reference numeral 1, 1 to designate a pair of inverted V shaped frames forming the side frames for the swing and adapted to rest upon the ground. Longitudinal braces 2 and transverse braces 3 connect the feet of the frames 1, lending strength to the swing construction. A cross piece 4 connecting the apices of the V shaped frames serves to support the intermediate portion of a canvas sun shade 5. The edges 45 of this canvas sun shade are secured to the intermediate portions of U shaped yokes 6 pivoted to opposite sides of the frames 1 adjacent their upper ends.

A pair of hangers 7 depending from the

cross piece 4 carry a rod 8 from which a 55 pair of arms or pendulums 9 pivotally depend. The arms 9 carry at their lower ends any convenient type of seat 10 for the reception of a person, or a doll in case the device is a toy. 60

The invention in this case resides principally in the provision of a spring motor, designated in its entirety by the reference numeral 11, for oscillating the seat. The motor is accommodated between a pair of plates 12, one of which is secured to the outer face of one of the frames 1 and the other of which is spaced from the first plate by suitable spacing devices 13. The spring motor may be of any conventional construction. I prefer to use a main drive shaft 14 provided with a suitable crank handle 15 for winding the spring 16 of the motor. The drive shaft may be connected through any number of suitable countershafts 17 and 70 speed increasing gears 18 to a driven shaft 20. The inner end of this shaft projects 75 inwardly through the plate 12 which is secured to the frame 1, and carries a crank arm 19 at the end of which, an inwardly presented pin 21 is fixed. 80

An outwardly extending stud 22 carried by the adjacent pendulum or arm 9 provides mounting for a wire 23, said wire including a spring loop 24 to cushion the movement 85 of the swing and including a depending elongated loop portion 25, accommodating the pin 21 of the crank arm 19.

When the device is in operation, the elongated loop 25 by virtue of the weight of the swing 10 acts as an escapement for the spring motor and the pin 21 by virtue of the intermittent rotation of the shaft 20 imparts an oscillating movement to the elongated loop 25 and through the medium of this loop to the pendulums 9 which carry the swing. 90

It is to be understood that this swing may either be used as a toy or as a full sized lawn swing.

Although I have illustrated one of the 100 preferred embodiments of my invention, it will be obvious that numerous slight changes might be made in the general form and arrangement of the parts described without departing from the invention, and hence I 105 do not wish to limit myself to the precise details set forth, but shall consider myself at liberty to make such slight changes and

alterations as fairly fall within the spirit and scope of the appended claim.

I claim:

A device of the character described comprising a frame, a swing pendently mounted in the frame, a stud fixed to the frame and projecting outward, a curved spring arm

having a depending elongated loop integral with it mounted on said stud, a crank arm having a stud fixed thereto, said stud making sliding engagement with the elongated loop, and a spring motor for operating the crank arm to operate the spring arm. 10

EUGENE GRIESHABER.
